(57) **CLAIM**

The ornamental design for a weighing apparatus, as shown and described.

DESCRIPTION

FIG. 1 is a bottom view of a weighing apparatus of our new design;

FIG. 2 is a front view thereof;

FIG. 3 is a left side view thereof;

FIG. 4 is a perspective view thereof

FIG. 5 is a rear view thereof;

FIG. 6 is a right side view thereof; and,

FIG. 7 is a top view thereof.

The broken lines shown in the figures are for the purpose of illustrating the environment and form no part of the claimed design.
